TOOTHBRUSH HOLDER

Roy G. McMillan, Windsor, Ontario, Canada

Application December 9, 1931, Serial No. 579,867

4 Claims. (Cl. 206—15.1)

The principal objects of the invention are to provide a cabinet in which a plurality of brushes may be retained so that they will be maintained in a sanitary condition and will be readily accessible and further, to provide a cabinet of extremely simple form which may be manufactured at low cost and will be of an attractive appearance.

A further object is to devise a cabinet which may be very readily cleaned and sterilized.

10 The principal features of the invention consist in the novel formation of a cabinet with a plurality of horizontally arranged partitions dividing the interior into a plurality of separate compartments in which the brushes may be individually arranged so that the bristles may be thoroughly dried and will not be disarranged by contact with any portion of the supporting structure.

15 A further feature of importance consists in the novel construction of the cabinet in a unitary moulded member having a single cover enclosing the various compartments and permitting a free circulation of air through the cabinet.

20 In the accompanying drawing, Figure 1 is a perspective view of the cabinet showing the cover in the open position partly broken away.

Figure 2 is a vertical sectional view of the cabinet taken on the line 2—2 of Figure 1 and showing the cover in its closed position.

25 Figure 3 is a vertical mid-sectional view taken 30 on the line 3—3 of Figure 1.

Figure 4 is an end elevational view.

Figure 5 is a perspective detail of a modified form of hinge support for the cover.

35 Numerous forms of cabinets for holding tooth brushes have been devised with the intent of holding the brushes separated the one from the other and provision has been proposed for providing means for sterilizing the brushes.

40 The present invention proposes a distinct improvement in providing a cabinet 1 which is preferably moulded in a unitary structure presenting smooth, hard surfaces which will resist moisture and corrosion and may be easily cleansed.

45 The back wall 2 of the casing is preferably arranged in an inclined position between the end walls 3 and the open front face is preferably parallel with the back wall.

50 Arranged within the casing and extending between the end walls 3 are a plurality of partitions 4 each of which is moulded integrally with or cemented to the back and end walls. These partitions are formed with the horizontal portions 5 extending the major length of the casing and are curved downwardly to a shorter length 6. The 55 length of the shorter portions of the partitions

are sufficiently long to permit the insertion of the bristle end of a tooth brush and the portions 5 are raised above the top surface of the portions 6 a sufficient distance so that when the handle of the brush rests upon the portion 5 the downwardly turned bristles will not contact with the surface of the portion 6.

The brushes will thus rest upon the handle portions upon the partition portions 5 and any moisture in the brush head will drip freely from the brush into the pocket portion, but as the partitions extend from end to end any moisture dripping from one brush will not drip upon any other brush in the cabinet.

50 Finger notches 7 are formed in the partitions 4 about mid-way of their length to enable the insertion of the finger and thumb to grasp the brush handle and to enable the brush being readily placed in position.

The bottom of the casing is formed with a 55 raised portion 8, the upper surface of which corresponds with the top surfaces of the partitions 4 and has a depression 9 in line with the notches 7 to enable the ready handling of the brush supported thereon.

60 The top 10 of the casing is preferably formed with recesses 11 adjacent to each end which are adapted to receive the hinge lugs 12 formed on the cover 13 and hinge pins 14 are inserted in holes 15 to pass through said lugs and form a 65 pivot support.

65 It may be found desirable to fasten the cover with an ordinary metal hinge or other designs of hinge construction may be devised, a modified form being shown in Figure 5.

70 The cover 13 is preferably moulded in one piece and is formed with a flanged edge 16 on the top and ends which engage the top and end edges of the casing.

75 The bottom edge of the cover is preferably formed without a flange so that air will enter freely all along the bottom to flow upwardly between the cover and the partitions and openings 17 are formed in the end flanges adjacent to the top to permit the air to escape. This arrangement provides for a free circulation of air which will evaporate any small amount of moisture dripping from the brushes and will also effectively dry the bristles in their suspended position.

80 Any suitable means for securing the cabinet on a wall or ledge may be provided on the back 2, but I show a pair of keyhole slots 18 in the back through which suitable screws may be inserted to hold the cabinet in place.

85 A cabinet such as described may be moulded in 110

a light metal such as aluminum or preferably in a plastic such as "bakelite" which finishes with a smooth polished surface direct from the mould and it will be very readily cleansed by rinsing with water or may be rendered sterile by dipping in an antiseptic solution or in boiling water.

5 A cabinet such as described not only enhances the sanitary features but ensures the maintenance of the brushes in a hygienic condition. The 10 brushes are suspended with the bristles turned downward and any moisture will be drawn away from the base of the bristles and be quickly evaporated and this very greatly lengthens the life of the brush and keeps it in a good condition. 15 Further the brushes are also hidden from view within a cabinet of attractive appearance.

The cabinet is preferably moulded from a plastic as described but it must be understood that it may be fabricated from separately formed pieces 20 cemented together.

What I claim as my invention is:—

1. A multiple tooth brush cabinet having a plurality of substantially horizontal partitions disposed one above the other forming individual 25 open-sided compartments and each forming a support for a separate tooth brush, said partitions being stepped downwardly at the end for a portion of their length to accommodate the bristle end of the brushes, whereby a plurality of tooth 30 brushes are nested in compact horizontally disposed but separated relation, and a door closing the open sides of all of said compartments.

2. A multiple tooth brush cabinet having a plurality of substantially horizontal partitions disposed one above the other forming individual 35 open-sided compartments and each forming a support for a separate tooth brush, said partitions having end portions depressed to accommodate the bristle end of the brushes whereby a plurality 40 of tooth brushes are nested in compact hori-

zontally disposed but separated relation, each partition having a deep recess retreating inwardly at a spaced point from the depressed portion thereof to expose a portion of the tooth brush handle to permit gripping thereof by the fingers, and a cover forming a closure for all of the compartments.

3. A multiple tooth brush cabinet having upright ends and a sloping rear wall interposed therebetween, a plurality of partitions of equal width extending substantially horizontally forward from said sloping rear wall forming a series of individual horizontal tooth brush receiving compartments of equal depth and staggered from the vertical in relation to each other, said partitions having portions in the length thereof depressed to accommodate the bristle end of the brushes, and a door adapted to swing into substantially parallel relation to said rear sloping wall to close all of said compartments.

4. A multiple tooth brush cabinet having a plurality of substantially horizontal partitions disposed one above the other forming individual open-sided compartments and each forming a support for a separate tooth brush, said partitions having portions in the length thereof depressed downwardly to accommodate the bristle end of the brushes, whereby a plurality of tooth brushes are nested in compact horizontally disposed but separated relation, and a cover hinged to the cabinet and having vertical side flanges engaging the end walls of the cabinet and spacing the cover from the forward edges of said partitions, said cabinet having openings at the upper end forming air outlet passages, whereby air is permitted to circulate upwardly past all of said compartments and outwardly through the upper openings to thoroughly ventilate all of the tooth brush compartments and dry the brushes therein.
